UNITED STATES PATENT OFFICE.

THOMAS HOLT, OF MIDLAND PARK, NEW JERSEY.

TERRY-LOOM.

SPECIFICATION forming part of Letters Patent No. 441,303, dated November 25, 1890.

Application filed October 6, 1887. Serial No. 251,616. (No model.)

To all whom it may concern:

Be it known that I, THOMAS HOLT, a citizen of the United States, residing at Midland Park, Bergen county, New Jersey, have invented certain new and useful Improvements in Terry-Looms, of which the following is a specification.

This invention relates to looms for weaving terry fabrics, such as Turkish toweling and the like.

The object of the invention is twofold: first, to enable the loom to weave a pile of varying thickness, whereby ribs or ridges or other patterns may be formed on the surface of the fabric by reason of the varying length of the loops forming the pile, and, second, to improve the construction of the existing terry motion, wherein the pile is formed by the pressing back of the reed through the medium of pivoted catches or dogs, which during the forward movement of the lay encounter fixed projections, and which at intervals are displaced in such manner as to clear the projections, in order to cause the pile to be beaten up. The latter feature of my invention is an improvement on the mechanism disclosed in the patent of Holt and Mellor, No. 327,685, dated October 6, 1885, of which I am the assignee.

Figure 1 of the accompanying drawings is a plan of part of a terry-loom constructed according to my invention, those portions of the loom which are not necessary to an understanding of the terry motion being omitted. Fig. 2 is a vertical transverse section thereof. Fig. 3 is a similar view to Fig. 2, showing the parts in a different position. Fig. 4 is a vertical longitudinal section showing the breast-beam and its attachments in rear elevation. Fig. 5 is an enlarged fragmentary transverse section of the lay, reed, and breast-beam. Fig. 6 is an enlarged fragmentary front elevation of the cam-motion for determining the variations in the height of the pile, the right-hand portion of the figure being a plan of one of the bumpers and the corresponding pivoted catch. Figs. 7 and 8 are diagrams illustrating the weave. Figs. 9 and 10 show a modified mechanism, Fig. 9 being a plan and Fig. 10 a vertical transverse section.

The frame A, breast-beam B, lay C, lay-swords D, rocking shaft E, crank-shaft F, and

picking-shaft G are or may be all of the usual construction. The lay is reciprocated through the medium of pitmen *a a* by cranks *b b* on the shaft F, as usual. The shaft F carries a gear *c*, which meshes with a gear *d* of twice its diameter, that is fixed on the picking-shaft G, whereby this shaft is driven at one-half the speed of the shaft F. On the shaft G is a pinion *e*, which meshes with a gear *f* one-and-one-half times its diameter, which is fixed on the cam-shaft H, whereby this shaft is caused to revolve once for each three revolutions of the shaft F. On the shaft H is fixed a cam I, which acts against a lever J, which is fulcrumed to one of the cross-girts A' A'.

The reed K is constructed, as usual, with top and bottom ribs, the upper rib being housed in a groove in the reed top or bar C', which is fixed rigidly to the lay, and the lower rib being confined in a groove in the movable reed-bar K', which is carried at the back of the lay and is pressed forward thereagainst by reed-springs L L, fastened to a cross-bar L', carried by the sword D, all as usual.

To the reed-bar K' are pivoted two (more or less) vertically-swinging catches, arms, or dogs M M, which extend forward through openings in the lay and project at the front of the lay sufficiently far to encounter when the lay is thrown forward corresponding stationary stops or projections N N, which I call "bumpers." These bumpers act to press back the projections or catches M and the reed-bar K' by holding them stationary while the lay is completing its forward or "beating-up" movement, thereby pressing back the reed, so that the weft thrown at the last pick will not be beaten up against the finished edge of the cloth, but will be left standing out at a short distance therefrom, corresponding to the extent to which the reed is pressed back. This pressing back of the reed by the striking of the catches M M against the bumpers occurs during two successive picks; but at the third pick the catches are thrown up, as shown in Fig. 3, so that they clear the bumpers and are not pressed back thereby. The catches are formed each with a hook or shoulder *m* on its upper side, so that when thus thrown up these hooks catch against the front surface of the lay, as seen in Fig. 3, and thereby fasten the reed-bar K' immovably to the lay, so that

the reed cannot be driven back by the resistance of the wefts during the operation of beating up those wefts which were previously left standing apart from the finished web. The 5 throwing up of the catches M M at each third pick is effected by the action of the cam I on the lever J, motion being communicated from this lever to the catches by mechanism which will be described presently.

10 So far as already described this loom does not differ materially from that shown in my said patent, No. 327,685. In weaving terry fabric by a loom of this construction and having the proportions described two wefts are 15 thrown which are not beaten fully up to the web of fabric, and upon the throwing of the third weft it and the two preceding wefts are beaten home. This last action is due to the throwing up of the catches M M by the cam 20 I at every third pick.

It is well understood that in weaving terry fabric the warp is of two kinds, a "ground warp," the threads of which are under considerable tension, and a "pile warp," the 25 tension of which is very slight. Upon the beating home of the wefts after the third pick, the pile warp, which is crossed between the wefts, is carried along with them, its tension being insufficient to pull it through 30 against the friction occasioned by the binding of the wefts against it, and it is consequently formed into loops, there being thus a row of loops to each three wefts. The tension on the ground warp, which is preferably 35 not so thoroughly interlocked with the wefts by being so often crossed, is sufficient to hold it from being carried forward with the wefts as they are beaten up.

It will be understood that instead of beating home the wefts at every third pick this 40 may be done at every second, fourth, fifth, or any number of picks, or at varying intervals, as may be desired, it being only necessary to this end that the proportions of the gears c 45 and d or e and f be so altered as to accord with the intervals desired.

I will now proceed to describe the novel features of my present invention.

The improved mechanism by which the 50 lifting motion is communicated from the cam I to the catches M M is constructed as follows: The lever J is fulcrumed at or near its middle, its rear arm coming beneath the cam I, and its front arm extending forward and 55 downward to a point preferably directly over the rocking shaft E, where the movement of the lay-sword is least. It is here jointed to a connecting-rod g, which extends upward, and the upper end of which is jointed to an 60 arm h, which is fixed to a horizontal shaft i, having bearings borne by the lay or lay-sword. To this shaft are fixed two arms i' i'', which project forward and terminate beneath the respective catches M M. To their front 65 ends are jointed lifting rods or pins j j, which project upwardly with their upper ends in contact with the under sides of the catches.

Their upper ends are guided by sliding freely through perforations in plates j', fastened to the front side of the lay. As the cam I acts 70 upon the lever J, the front end of the latter rises, pushing up the rod g, rocking the shaft i, and raising the pins j j, which push up the catches M M. This mechanism is superior to that shown in my said patent in that it is subject to less friction and wear. 75

The other feature of my present invention relates to means for automatically varying the thickness or depth of the pile laid up by the terry motion, in order that the successive 80 rows of loops may stand at different heights in order to produce a ribbed effect on the surface of the fabric. It will be understood that the depth of the pile depends upon the extent to which the reed is pressed back by the action 85 of the bumpers upon the catches. In my said previous patent the bumpers are made in the form of screws, which may be screwed in or out to adjust their projection from the face of the breast-beam, and thereby to alter 90 at will the depth of the pile.

To accomplish the purpose of my present invention, it is necessary that the extent of projection of the bumpers shall be altered automatically and instantaneously during the 95 operation of the loom, instead of being varied by adjustment. This action may be accomplished by any mechanism which will automatically vary the extent of projection of the bumpers, or substitute for one bumper another one of greater or less projection during the operation of the loom and between the successive picks in any order that may be requisite to produce any desired effect upon the depth of the pile. It is preferable to effect the change in the extent of projection of the bumper during the pick or picks at which the catches M M are lifted out of engagement with the bumpers, since at this time the bumpers are not acting. 100

If it is desired, for example, that every alternate row of pile-loops shall be higher than the others, the bumpers will be constructed to stand at a low projection during the picks between one "driving-up pick" and the next 115 and then to shift to a higher projection and stand at that during the picks occurring before the next ensuing driving-up pick is reached. This is the simplest operation in weaving a terry fabric with a pile of varying 120 depth. For a pile graded in loops of three or more different heights the operation will be more complicated.

Perhaps the best example for illustrating the practical application of my invention is 125 the case of a pile graded in loops of three different heights, which succeed each other in ascending and descending order. It is for weaving a pile fabric of this character that the mechanism illustrated in Figs. 1 to 6 is 130 designed. I will now proceed to describe this apparatus. The bumpers N N are formed in steps of three different projections, as best shown in Fig. 1, all being arranged in the

same horizontal plane and side by side, so that to bring a higher or lower step into the path of the catch it is necessary to move the bumper in lateral direction a distance equal to the width of the step. To effect this movement the two bumpers are mounted on a horizontally-sliding bar O, which has beveled edges confined in dovetailed grooves in bearing-blocks O', fastened to the rear side of the breast-beam B. The bar O is drawn in one direction (leftwardly in Fig. 1) by a spring k, and is pressed in the other direction by a cam P, which takes against the left-hand end of the bar. This cam is best shown in Fig. 6. Its perimeter has its working-face formed of arcs of four different radii, corresponding to the position of the three different steps on the bumpers and the space beyond the lowest step. Each section of the working-face of the cam is of a length equal to two eighteenths of a revolution, and between each two working faces is an inclined or shifting face which occupies approximately one-eighteenth of a revolution. The cam is rotated one-eighteenth of a revolution at each pick, and its position relatively to the cam I and the other mechanism is such that during the dwell of the sliding bar O, while each section of the working-face of the cam is bearing against it, two picks are made, at which the catches M M encounter the bumpers, and upon the next or third pick and while the catches are thrown up so as to free them from the bumpers the inclined or shifting face of the cam P is acting upon the bar O and shifts it the distance from one bumper-step to the next, so that the next time the lay comes forward the catches will encounter different steps on the bumpers.

Referring to Fig. 6, the respective bumper-steps are lettered n' , n^2 , and n^3 , and the corresponding working-faces of the cam P are lettered p' , p^2 , and p^3 . The cam P has also a fourth working-face lettered p , the effect of which is to move the bumpers so far to the left that they are entirely out of the paths of the catches M M, so that for three picks every weft is beaten home as soon as it is thrown, thereby weaving the fabric during this interval without any pile.

The operation may be best understood by a comparison of Fig. 6 with the diagrams, Figs. 7 and 8. These diagrams are longitudinal sections, the weft-threads being shown in transverse section and the pile warp being shown in side view. The ground warp is not shown, being well understood. It may be of any customary weave. Every third weft is designated by a black cross-section to distinguish the driving-up picks. Eighteen successive wefts are shown, being those thrown during one complete revolution of the cam P. Wefts Nos. 1, 2, and 3 are thrown while the working-face p of the cam is against the bar O, as shown in Fig. 6 in full lines, so that the bumpers do not act upon the catches. Each weft is thus beaten home as soon as it is thrown,

the tension of the reed-springs L being sufficient to accomplish this during the first and second picks while the catches are out of action. During the third pick the shifting-face of the cam acts upon the bar O and moves it far enough toward the right to bring the first step n' of each bumper into the path of the corresponding catch, so that during the fourth and fifth picks (while the working-face p' of the cam is presented to the bar O) the catches encounter this step of the bumpers and the reed is pressed back a distance equal to the height of the step, so that wefts Nos. 4 and 5 are left standing apart from the finished portion of the fabric, as shown in Fig. 7. At the sixth pick the catches are thrown up, and wefts Nos. 4, 5, and 6 are beaten home, thereby raising the pile warp covering wefts Nos. 3 and 4 to form loops, as shown in Fig. 8, where these loops are lettered x . During this sixth pick the cam P has moved the bar O still farther to the right, thereby bringing the second steps n^2 of the bumpers into the paths of the catches, where they remain during the two following picks, while the working-face p^2 is presented against the end of the bar. Wefts Nos. 7 and 8 are consequently left standing farther out from the finished portion of the web than was the case with Nos. 4 and 5, Fig. 7, in proportion to the greater projection of step n^2 , as compared with step n' . Upon the ninth pick wefts 7, 8, and 9 are beaten home, thus forming loops y in Fig. 8, and the cam P moves bar O still farther to the right, bringing the highest steps n^3 of the bumpers into the path of the catches, where they will remain during the two ensuing picks, while the working-face p^3 is presented to the bar O. The catches on encountering this highest step of the bumpers are pressed back farther than before, so that the reed in beating up wefts Nos. 10 and 11 leaves them at a still greater distance from their predecessors than before, as shown in Fig. 7, so that on the beating up after weft No. 12 is thrown the pile warp is formed into still higher loops z , Fig. 8. During this beating-up pick the return movement of the bar O by the cam has begun, bringing step n^2 again into the path of the catches, whereupon wefts 13 and 14 are thrown, and after 15 is thrown the beating-up movement forms the loops y' in Fig. 8. During this fifteenth pick another drop in the cam occurs, bringing step n' again into the path of the catches, whereupon wefts Nos. 16 and 17 are thrown, on the beating up of which, after the throwing of 18, the loops z' in Fig. 8 are formed. During this eighteenth pick the final drop in the cam occurs, bringing its working-face p again against the bar O, which has now resumed the position of starting, an entire revolution of the cam having taken place. The fabric thus formed has loops of varying height, each loop inclosing or bridging two wefts, and each row of loops being separated from the next row by one

weft, and each series of five rows being separated from the next by four wefts woven without pile.

It will be understood that the fabric may be varied in a great variety of ways by merely effecting a corresponding variation in the gearing and proportions of the mechanism. The height of the respective loops will depend upon the amount of projection of the relative steps with which the bumpers are formed, and is best altered by removing the bumpers and replacing them with others of different proportions.

The cam P may be rotated either continuously or intermittently by any mechanism whatever that is adapted to the purpose. With the proportions shown it must, as stated, make one-eighteenth of a revolution to each pick. I prefer to rotate it intermittently, and I have shown one mechanism which is well adapted to accomplish this, and which I will now describe; but I wish it well understood that in its generic features my invention is by no means limited to this or any similar mechanical movement for accomplishing this purpose. The cam P is fastened to a ratchet-wheel Q, having eighteen teeth, as shown in Fig. 6, and which turns on a stud q, fixed to the rear side of the breast-beam. This ratchet-wheel is engaged by a pawl R, which consists of a rod, the upper end of which is bent horizontally and enters the notches in the ratchet-wheel, while its lower end extends down along the front frame of the loom and is jointed to the horizontal arm of an elbow-lever S, pivoted to the front frame, and the vertical arm of which extends upwardly and is jointed to a connecting-rod r, whose opposite end is pivoted to the lay or lay sword, its connection therewith being made by means of a hinge-plate s. As the lay moves forward to beat up the weft, its motion is communicated through the rod r to the lever S, which it tilts, thereby raising the rod R, the upper end of which passes up over one tooth of the ratchet-wheel Q, and on the rearward movement of the lay the rod R descends, its upper end pulling down the tooth of the ratchet-wheel with which it has thus engaged, and thereby turning the ratchet-wheel the distance from one tooth to the next. A spring l serves to press the rod R toward the ratchet-wheel, in order to insure its engagement therewith. By this construction the cam is advanced during the rearward movement of the lay. This, however, is not essential, as it may be done as well during the forward movement of the lay by merely reversing the ratchet-wheel. In changing to a cam constructed for a different cycle of movements than eighteen a correspondingly-different ratchet-wheel will be substituted—that is, one having more or fewer teeth, corresponding in number to the cycles of movements for which the cam is designed. In such case it may be necessary to vary the throw of the pawl R. This is done by con-

necting the rod r to the lay-sword at a point nearer to or farther from the shaft E, in order to impart a lesser or greater movement to the lever S. To this end the hinged plate s is made removable, so that it may be set at any height on the lay-sword. The connecting-rod r is made in two pieces sliding upon one another and fastened by screws r² at any point, 75 so that it may be extended or shortened to adapt it to any position to which the plate s may be set.

Figs. 9 and 10 illustrate a modification, wherein the bumpers are moved forward and back instead of sidewise, and are actuated by a continuously-rotating instead of by an intermittent mechanism. The bumpers are made in the form of screws, as in my said previous patent, passing through the breast-beam and engaging internal threads in sockets set therein. The height of the pile loops depends upon the extent to which the screws are screwed backward, and this is continually varied during the operation of the loom. 90

Each bumper N consists of a screw T, screwing into a socket T', fastened to the rear of the breast-beam, and having fixed to it a pinion t, which meshes with a sliding rack U, which is arranged to slide in lateral direction parallel with and in front of the breast-beam, being guided in ways formed in brackets u, which serve also to support the front ends or journals of the screws. As this rack U is reciprocated, the pinions t and screws T are thereby rotated back and forth, and the screws are caused to travel longitudinally, so that their ends project to greater or less distances from time to time to the rear of the breast-beam and in the path of the catches M M. The rack U is reciprocated by a crank V through the medium of a pitman v. The crank V is fixed on a shaft V', carrying a bevel-gear W, with which meshes a bevel-pinion W', which is fixed on a shaft w, having a bearing in the frame of the loom, and carrying fixed on its outer end a sprocket-wheel X, which is geared by chain X' to another sprocket-wheel Y', which is fixed on the shaft G, or on any other suitable shaft of the loom. Through the medium of this gearing the crank V is driven at a suitably-reduced speed—say, for example, at the rate of one revolution to eighteen picks. 105

The operation is evident. When the crank V is at one end of its throw and passing its dead-center, the screws T are screwed out so that their bumper ends have the minimum of projection, as shown in full lines in Fig. 9; and when the crank is at the opposite end of its throw the screws are screwed fully back and their bumper ends have the maximum of projection, as shown in dotted lines in Fig. 9. In the intermediate positions of the crank the bumpers are projected to an intermediate extent. The full-line position in Fig. 9 corresponds to the full-line position in Fig. 6, the catches being at this time not acted upon by the bumpers. 110 125 130

The modification here described is illustrated merely as an example of the numerous modifications in the construction of the driving mechanism or gearing of which my invention is capable, and which may be readily devised by any skilled mechanic familiar with the principle introduced by my invention.

My invention may be applied to the weaving of figured terry fabrics, and to those having the pile on only one side, the other side or back being woven without a pile. These and other variations in the fabric will be made according to the skill and taste of the weaver, and by the methods already well known in the art.

It will be understood that my invention for automatically varying the depth of the pile may be applied in connection with almost any kind of terry-motion, and is not confined in its application to the particular type of terry-motion covered by my said patent. It is very readily applicable to all terry-motions in which the reed is so mounted that it can be pressed back and is provided with some kind of projections analogous to and equivalents of the projecting catches M M, herein described. It will also be understood that in case my said patented terry-motion is used the catches M M may be hung to be thrown in any direction to disconnect them from the bumpers for the beating-up picks, and that they are not essentially limited to a vertical movement.

In defining my improvements in the claims which terminate this specification I use the expression "loom-driving mechanism" to indicate such driving-shafts and their accessories as are employed to impart the requisite movements to the essential parts of the loom. I use the term "terry-motion" to indicate the parts by which the reed is displaced at certain picks to form the pile and is at certain other picks freed to enable it to beat home the wefts and throw up the loops, and I employ the name "gearing" to denote any combination of coacting mechanical elements by which motion is communicated from one moving part to another and converted from one character of movement to another, as in what are generically known as "mechanical movements."

I claim as my invention the following-defined improvements in terry-looms, substantially as hereinbefore specified, namely:

1. The combination, with the loom-driving mechanism, lay, and reed, and the terry-motion consisting of pivoted projections on the reed designed to encounter bumpers for displacing the reed to form the pile and mechanism for moving said projections at intervals out of engagement with said bumpers, of the said bumpers mounted on the frame and constructed to be movable relatively to the said projections in such manner as to project to a greater or less degree into the paths thereof, and thereby to vary the degree of displacement of the reed, and gearing inter-

posed between the driving mechanism of the loom and said bumpers and adapted to automatically shift the latter from time to time 70 during the weaving from a greater to a lesser projection, whereby the terry fabric is woven with a pile of varying depth.

2. The combination, with the loom-driving mechanism, lay, and reed, and the terry-motion consisting of projecting catches pivoted to the reed and formed with hooks adapted when the catches are displaced to engage the lay and fasten the reed thereto and mechanism for so displacing said catches at intervals, 80 of bumpers mounted on the frame of the loom in position to be encountered by and to displace said catches when the latter are in their normal position, and constructed to be movable relatively to said catches in such 85 manner as to project to a greater or less degree into the paths thereof, and thereby to vary the degree of displacement of the reed, and gearing interposed between the driving mechanism of the loom and said bumpers 90 and adapted to automatically shift the latter from time to time during the weaving from a greater to a lesser projection, whereby the terry fabric is woven with a pile of varying depth.

3. The combination, with the loom-driving mechanism, lay, and reed, and the terry-motion consisting of pivoted projections on the reed designed to encounter bumpers for displacing the reed to form the pile and mechanism for moving said projections at intervals out of engagement with said bumpers, of the said bumpers mounted on the frame and constructed to be movable into and out of the path of said projections and gearing interposed between the driving mechanism of the loom and said bumpers and adapted to so move the latter automatically during the weaving, whereby the terry fabric is woven with an intermittent pile, the portions thereof having 110 no pile being woven during the time that the bumpers are moved out of the paths of said projections.

4. The combination, with the loom-driving mechanism, lay, and reed, and the reed mounted movably on the lay, provided with springs tending to hold it in place therein and having projections designed to encounter bumpers on the frame for displacing the reed to form the pile, of the said bumpers constructed 120 with steps of different degrees of projection and mounted to slide on the frame in such direction as to move across the path traversed by said projections on the reed and bring either step thereof into the path of said projections 125 in order thereby to vary the degree of displacement of the reed, and gearing interposed between the driving mechanism of the loom and said bumpers and adapted to so move the latter automatically from time to 130 time during the weaving, whereby the terry fabric is woven with a pile of varying depth, and mechanism for moving the projections and bumpers relatively out of engagement

at intervals in order to cause the pile to be beaten up.

5. The combination, with the loom-driving mechanism, lay, and reed mounted movably in the lay and provided with springs tending to hold it in place therein and having projections designed to encounter bumpers on the frame of the loom for displacing the reed to form the pile, of the said bumpers constructed with steps of different degrees of projection and mounted to move on the frame in direction across the path traversed by said projections on the reed to bring either step thereof into engagement with said projections and to move out of the path of said projections, so that the reed shall not be displaced, and gearing interposed between the driving mechanism of the loom and said bumpers and adapted to so move the latter automatically during the weaving, whereby the terry fabric is woven with an intermittent pile, the portions thereof having no pile being woven during the time that the bumpers are moved out of the paths of said projections, and the piled portions thereof being woven with a pile of varying depth, and mechanism for moving the projections and bumpers relatively out of engagement at intervals in order to cause the pile to be beaten up.

30 6. The combination, with the loom-driving mechanism, lay, and reed, the latter having projections connected to the reed and designed to encounter bumpers on the frame of the loom for displacing the reed to form the pile, of the said bumpers constructed with steps of different degrees of projection and mounted on the frame in such manner as to be movable laterally across the path traversed by said projections on the reed in order to bring either step thereof into the path of said projections, and thereby to vary the degree of displacement of the reed, a cam connected to said bumpers and constructed to move the latter from time to time the distance from one step to the next, and gearing interposed between the driving mechanism of the loom and said cam, whereby the latter is driven.

7. The combination, with the loom-driving mechanism, lay, and reed, of projections connected to the reed and designed to encounter bumpers on the frame of the loom for displacing the reed to form the pile, the said bumpers, a slide mounted on the breast-beam and to which said bumpers are attached, whereby by the sliding of said slide the bumpers are moved across the paths traversed by said reed projections, and gearing interposed between the driving mechanism of the loom and said slide and adapted to impart a reciprocating movement to the latter.

8. The combination, with the loom-driving mechanism, lay, and reed, of projections connected to the reed and designed to encounter bumpers on the frame of the loom for displacing the reed to form the pile, the said bumpers constructed with steps of different degrees of projection and mounted on the frame in

such manner as to be movable laterally across the path traversed by said projections on the reed, in order to bring either step thereof into the path of said projections, and thereby to vary the degree of displacement of the reed, a cam connected to said bumpers and constructed to move the latter from time to time the distance from one step to the next, a ratchet-wheel connected to said cam, and the pawl of said ratchet connected to and reciprocated by some moving part of the loom, whereby said cam is rotated intermittently.

9. The combination, with the loom-driving mechanism, lay, and reed, the latter having projections M M, of the bumpers N N, sliding bar O, on which the bumpers are mounted, pile-cam P for moving said sliding bar to carry the bumpers across the paths of said projections, and gearing interposed between the driving mechanism of the loom and said cam for rotating the latter.

10. The combination, with the loom-driving mechanism, lay, and reed, the latter having projections M M, of the bumpers N N, sliding bar O, on which the bumpers are mounted, pile-cam P for moving said sliding bar to carry the bumpers across the paths of said projections, ratchet-wheel Q, pawl R thereof, and connecting mechanism between the lay and said pawl for reciprocating the latter coincidently with the vibration of the lay.

11. The combination, with the loom-driving mechanism, lay, and reed, the latter having projections M M, of the bumpers N N, mounted on the frame of the loom and constructed to be movable in such manner as to project to greater or less degree into the paths of said projections M M, a cam P, connected to and adapted to so move said bumpers, a ratchet and pawl for driving said cam, and connecting-gearing between said pawl and the lay, having an adjustable connection with the lay, whereby the play of the pawl may be varied by connecting said gearing nearer to or farther from the center of vibration of the lay.

12. The combination, with the loom-driving mechanism, lay, and reed, of the terry-motion consisting of pivoted projections on the reed, bumpers to be encountered thereby for displacing the reed to form the pile, and mechanism for moving said projections at intervals out of engagement with said bumpers during one or more beating-up picks, the said bumpers mounted on the frame of the loom and constructed to be movable relatively to said projections in such manner as to project to a greater or less degree into the paths thereof, and thereby to vary the degree of displacement of the reed, and gearing for moving said bumpers connected to and driven by the driving mechanism of the loom, and constructed to effect the movement of the bumpers from one degree of projection to another during the beating-up picks only, whereby the bumpers are moved while the reed projections are disconnected from them, and in the fabric the transition from one

depth of pile to another is effected between successive rows of loops.

13. The combination, with the loom-driving mechanism, lay, and reed, and the terry-motion consisting of pivoted projections on the reed designed to encounter bumpers for displacing the reed to form the pile and mechanism for moving said projections at intervals out of engagement with said bumpers 5 during one or more beating-up picks, of the said bumpers mounted on the frame of the loom and constructed to be movable relatively to said projections in such manner as to project to a greater or less degree into the paths thereof, and thereby to vary the degree of displacement of the reed, and gearing for moving said bumpers, consisting of a reciprocating part connected to the bumpers in such manner that when moved in one direction it 10 projects them to a greater and when moved in the contrary direction it projects them in a lesser degree into the paths of said reed projections, and connections with the driving mechanism of the loom for reciprocating said 15 part, whereby the fabric is woven with a pile of alternately increasing and diminishing depth.
14. The combination, with the loom-driving mechanism, lay, and reed, and bumpers on the breast-beam, of the terry-motion consisting of vertically-swinging catches M M, pivoted to

the reed, cam I, for determining the lifting of said catches at intervals, and mechanism for communicating the motion from the cam to the catches, consisting of a lever acted on by 35 the cam and terminating in an arm extending closely adjacent to the pivotal axis of the lay, and a rod connecting to said lever-arm and carried by the lay, so that it vibrates with the lay while moving up and down with the 40 lever, and a connection between the upper part of said rod and the catches, whereby its up-and-down movement is transmitted to them.

15. The combination, with the loom-driving 45 mechanism, lay, and reed, and bumpers on the breast-beam, of the terry-motion consisting of vertically-swinging catches M M, pivoted to the reed, cam I, for determining the lifting of said catches at intervals, and mechanism for 50 communicating the motion from said cam to the catches, consisting of lever J, rod g, shaft i, having arms h and i', and lifting-pins j j, taking under the catches.

In witness whereof I have hereunto signed 55 my name in the presence of two subscribing witnesses.

THOMAS HOLT.
